UNITED STATES PATENT OFFICE.

JOSEPH KELSO AND WILLIAM KELSO, OF PITTSBURGH, PENNSYLVANIA, ASSIGNORS TO McCONWAY & TORLEY COMPANY, OF PITTSBURGH, PENNSYLVANIA, A CORPORATION OF PENNSYLVANIA.

CAR-COUPING.

1,094,721.

Specification of Letters Patent. Patented Apr. 28, 1914.

Application filed January 2, 1913. Serial No. 739,678.

To all whom it may concern:

Be it known that we, JOSEPH KELSO and WILLIAM KELSO, citizens of the United States, residing at Pittsburgh, in the county 5 of Allegheny and State of Pennsylvania, have invented certain new and useful Improvements in Car-Couplers; and we do hereby declare the following to be a full, clear, and exact description of the invention, such as will enable others skilled in the 10 art to which it appertains to make and use the same.

Our invention relates to the construction of car couplers of the twin jaw M. C. B. 15 type, and its primary object is to produce simple, easily operated and efficient devices, borne by the coupler head and extending beneath the same, for controlling the unlocking of the coupler from the side of the car and for preventing an accidental unlocking 20 movement of the coupler lock, as well as for preventing undue vibration of the lock-actuating devices when the coupler is in service. These several objects are accomplished 25 by the combination of elements hereinafter described and claimed.

In the drawings illustrating our invention, the scope whereof is pointed out in the claims, Figure 1 is a plan view of a car coupler embodying our invention; Fig. 2 is a 30 side elevation of the mechanism illustrated in Fig. 1; Fig. 3 is a front elevation of the coupler; the relative positions of the lever and its catch when in locked position being 35 shown in full lines, and the position of the catch when rotated to release the lock actuating lever being shown in dotted lines; and Fig. 4 is a front elevation of the coupler showing the positions assumed by the parts 40 when the coupler is unlocked.

We will now proceed to describe our invention more fully, so that others skilled in the art to which it appertains may apply the same.

45 In the drawings, 1 indicates the coupler head, 2 the knuckle pivotally mounted thereon by means of a knuckle pin 3, and 4 a vertically movable gravity lock by which the outward rotation of the knuckle is restrained. Formed upon the outside of the 50 coupler head, and preferably upon the knuckle side thereof, are downwardly projecting perforated lugs 5 and 6 which receive a pivot pin 7 that serves to rotatably secure the 55 lock actuating lever 8 between them. These

lugs 5 and 6, as shown, are preferably so formed and arranged as to locate the point of pivotal connection of the lever 8 with the coupler head 1 well below the center of the head and to the rear of the lugs which 60 receive the knuckle pin 3. Pivotally mounted upon the coupler head 1 by means of the lugs 5 and 6 and the pivot pin 7 is a vertically oscillating bell-crank lever 8 whose lower arm, 8^a, extends under the coupler head and 65 far enough below the same to permit said lever arm to engage the coupler lock 4 and move it to unlocked position. As will be seen upon reference to Figs. 3 and 4 of the drawings, the arms of the bell-crank lever 8 70 are so related to its pivotal point that the lever has a constant tendency or bias to gravitate toward and remain in the locked position illustrated in Figs. 1, 2 and 3.

Mounted upon the upper arm 8^b of the 75 bell-crank lever is a catch 9 which is movable with and also independently of the lever 8. In mounting this catch upon the bell-crank lever it is preferred to secure the same to the upper end of the lever arm 8^b 80 by means of a pivot pin 10 that passes through the lever and through correspondingly perforated pivot lugs 9^a, 9^b which embrace the lever and are integrally united to the catch 9. To limit the extent of rotation 85 of the catch 9 with respect to the lever 8 and also for the purpose of providing means whereby the unlocking lever may be rotated on its pivot 7 through force applied to the catch 9, the latter is preferably provided 90 with stops or shoulders 9^b and 9^c which are adapted to respectively engage corresponding stops or abutments 8^c and 8^d formed upon the bell-crank lever. If desired the upper arm 8^b of the lock actuating 95 lever may also be provided with a projecting lug 8^e which, by engaging the wall of the coupler head 1 arrests the locking rotation of the lever 8 as the locking member or hook 9^d of the catch 9 moves into locked 100 position behind the corresponding locking face or abutment 1^a formed upon the coupler head 1.

In order to lead the hook 9^d of the catch 105 into locked position behind the catch-locking face 1^a of the coupler, the coupler head 1 is preferably provided adjacent to the locking face 1^a with upwardly extending guide lugs 1^b and 1^c which flank the face 1^a. As more particularly shown in Figs. 1 and 2 the up- 110

per ends and opposed or inner faces of these guide lugs are rounded or beveled in order the more certainly to direct the catch 9 to its proper locked position. The outer face of the hook member 9^a of the catch, as well as the outer portion 1^a of the coupler head in alignment with the locking face 1^a, is also preferably rounded or beveled, as illustrated in Fig. 3, so as to permit the hook 9^a to readily ride up over the surface 1^a of the head and fall behind the locking face 1^a when the catch 9 is moving to locked position.

As a means of actuating the catch 9 and bell-crank lever 8 from the side of the car it is preferred to employ a transversely extending slideable bar 11 having at its inner end an eye 11^a which receives a curved lug or finger 9^b that is formed upon the catch 9 and extends above the locking member or hook 9^a thereof. This construction facilitates the connection of the slideable uncoupling bar 11 to the catch 9; and it will also be noted that the location of the curved finger 9^b and locking hook 9^a on the same side of the vertical passing through the pivotal center 10 of the catch results in utilizing the weight of the pull-rod 11 to assist in maintaining the catch 9 in locked position.

Where, as in the case illustrated in the drawings, the lock 4 of the coupler is a vertically sliding gravity lock it is preferably provided with an integral extension 4^a which projects downwardly through the lower wall 35 of the coupler head and which is provided at its lower end with an aperture 4^b into which the end of the transversely extending arm 8^a of the bell-crank lever 8 projects. This arrangement, as will be readily perceived, permits the bell-crank lever 8 to move the lock 4 in either a locking or an unlocking direction, causes the force of gravity due to the weight of the lock to be transmitted to the lever 8 when the lock is 45 moving downward toward locked position, and also results in preventing the unlocking of the coupler except by an accompanying rotation of the bell-crank unlocking lever 8.

The operation of the devices hereinbefore described is as follows: Assuming the several parts to be in their normal or locked positions, as illustrated in Figs. 1, 2 and 3, a pull exerted upon the rod 11 will cause the catch 9 to rotate upon its pivot pin 10, thus 50 disengaging the locking hook 9^a of the catch from the corresponding locking face or abutment 1^a of the coupler head 1. When the unlocking rotation of the catch 9 has progressed far enough to bring its stop face 9^c 55 into engagement with the stop 8^a at the upper end of the bell-crank lever 8, as indicated in dotted lines in Fig. 3, the continued pull upon the uncoupling bar 11 causes the catch 9 and attached lever 8 to turn together 60 around the pivot pin 7 of the lever as a

center, thus causing the lower lever arm 8^a to force the lock 4 to execute an unlocking movement, as illustrated in Fig. 4. The force of gravity acting on the lock 4 and associated lock-actuating devices will cause 70 the parts to return to the locked position shown in Figs. 1, 2 and 3 when the pull upon the rod 11 is released and the lock is free to reassume a locked position; but if by reason of the presence of dirt, ice or the like the parts should fail to return to locked position when they properly should do so, it will be seen that they may be caused to 75 positively move to their respective locked positions by pushing upon the rod or bar 11, the engagement of the shoulder 9^b of the catch with the corresponding stop shoulder 8^c of the bell-crank lever 8 enabling the force thus applied by the bar 11 to the catch 9 to be transmitted to the lever 8 so as to 80 cause the latter to perform a locking rotation which will return the knuckle lock of the coupler to locked position. In returning to locked position the bell-crank lever 8 rotates upon the pivot pin 7 until arrested 85 by the engagement of its projecting lug 8^a with the coupler head 1, and the locking member or hook 9^a of the catch 9 falls into locked position behind the corresponding locking abutment 1^a of the coupler head. 90 As heretofore explained, an accidental unlocking of the coupler is impossible when the parts are in this position, for an unlocking movement of the coupler lock is necessarily accompanied by a rotation of the lever 8; 95 but such rotation is prevented by the catch 9. 100

We claim:

1. In a car coupler, the combination with the coupler head knuckle and coupler lock, of a lever mounted upon the outside of the 105 coupler head and pivotally connected to the same, a catch pivotally mounted on one arm of the lever, and means for rotating the catch on its pivot independently of the lever and for simultaneously rotating the catch and lever about the pivotal connection of the lever with the coupler head, said lever having an arm which engages and actuates the coupler lock and said catch and coupler head being provided with locking means for 110 preventing rotation of the lever in one direction until after disengagement of the said locking means of the catch and coupler head. 115

2. In a car coupler, the combination with the coupler head, knuckle and coupler lock, of a bell-crank lever pivotally mounted upon the outside of the coupler head and having one of its arms extending transversely of the coupler head to engage and actuate the coupler lock, a catch pivotally mounted 120 upon the other arm of the lever, and means for rotating said catch both with and also independently of the lever, said catch being provided with a locking member and said coupler head being provided with a cor- 125 130

responding locking face, and said catch and lever being provided with co-acting stops which limit the rotation of the catch with respect to the lever in one direction.

- 5 3. In a car coupler, the combination with the coupler head, knuckle and coupler lock, of a lever mounted upon the outside of the coupler head and pivotally connected to the same, a catch movably mounted upon one
 10 arm of the lever, said catch being provided with a locking member and said coupler head being provided with a corresponding locking face, means for limiting the movement of the catch with respect to the lever,
 15 means for rotating the catch and lever in either direction about the pivotal connection of the lever with the coupler head, and means for connecting the coupler lock and lever so as to permit the lever when moved
 20 in one direction to apply force to the coupler lock for moving the latter to unlocked position and when moved in the opposite direction to apply force to the coupler lock in an opposite direction.
 25 4. In a car coupler, the combination with the coupler head, knuckle and coupler lock, of a bell-crank lever mounted upon the outside of the coupler head and pivotally connected to the same, one arm of said lever ex-
 30 tending under the coupler head and being loosely connected to the coupler lock and the other arm of said lever extending upwardly from the pivotal point of the lever, a catch

pivots mounted upon the upper end of the upwardly extending lever arm, and an 35 operating bar loosely connected to said catch and adapted to rotate the same, said catch being provided with a locking member and said coupler head being provided with a corresponding locking face, and said catch and 40 lever being provided with means for limiting the rotation of the catch with respect to the lever.

5. In a car coupler, the combination with the coupler head, knuckle and coupler lock, 45 of a bell-crank lever mounted upon the outside of the coupler head and pivotally connected to the same, one arm of the lever engaging the coupler lock to actuate the latter, a catch pivotally mounted on the other arm 50 of the lever, said catch and coupler head being provided with locking means for preventing an unlocking rotation of the lever until after disengagement of said means, and means for moving said catch independ- 55 ently of said lever, said lever and catch having a bias to rotate in the same direction.

In testimony whereof we affix our signatures, in the presence of two subscribing witnesses.
